UNITED STATES PATENT OFFICE

LEON FREEMAN, OF CHICAGO, ILLINOIS

LABEL

Application filed July 30, 1931. Serial No. 553,988.

These improvements relate to labels adapted to be applied to articles of clothing, neckties, belts, etc., to identify the manufacturer or dealer, exhibit trade-marks, addresses, or other advertising. There is a large industry in labels for such applications, and their manufacture is one of the well known arts.

The present label is distinguished by the provision of a tongue-like clip or hook there-with adapted for engagement with some other article or part of the same article.

It has been customary to apply clips to various articles, for example neckties, for holding parts of the necktie together or the necktie as a whole to the wearer's shirt, and various inventions have been directed to such clips or holding means. The usual label is applied also to such articles.

According to the present invention I effect various savings of time and money, promote convenience, avoid the attachment of a plurality of items to the article, provide a better appearance for the article, and enable the clip to be secured more readily, more strongly and more advantageously to the article by securing the clip to the strong and firmly woven label which is then attached to the article.

In the drawing Figure 1 is a face view of my improved label in a highly advantageous form;

Fig. 2 is a rear view of the same;

Fig. 3 is a perspective of the clip device;

Fig. 4 shows the application of such a label to the band of a garment;

Fig. 5 shows its application to a necktie; and

Fig. 6 shows its application to a belt.

The label 10 may be of the usual form and construction, namely as a section or piece of finely and strongly woven fabric, usually in ribbon form and cut to length. Such labels are usually ornamental, of silk or satin, and embroidered. They are designed chiefly to carry such advertising or identifying data as the name of the manufacturer or distributor of or dealer in the article to which the label is attached, his trade-mark, business address, etc. Such data are shown at 11.

The clip device 12 is of thin springy sheet metal, having a substantially flat base or body 14 preferably of rectangular shape, and formed with an integral tongue-like springy clip element 15, while at its ends there are 55 slots or openings 16 for sewing the body to the label. The clip may be otherwise secured, but such sewing as at 17 may be done rapidly by machinery and is a highly satisfactory way to unite the clip body strongly and permanently to the label.

The body 14 is applied to the rear surface or side of the label as 10, with the springy leaf or clip 15 extending through an opening at 18 in the label, the clip then extending reversely back over the plane of the base and over the front surface of the label. When the label is applied to the article, as by stitching in the usual way at 20 (Figs. 4, 5 and 6) the tongue as 15 (Fig. 5), 21 (Fig. 4) and 22 (Fig. 6) is the only part of the catch device visible. This is not only ornamental and attractive in appearance, but it leaves substantially the whole face of the label free for the advertising such as 11.

In Figs. 4 and 6 the clip elements 21 and 22 respectively extend transversely of the label. Fig. 4 shows how the garment may be suspended from the clip as by hooking the clip over the upper edge of the trousers. In Fig. 6 the label is applied to a belt 25 and the clip 22 holds the ring 26 of what may be a chain for a watch or a bunch of keys.

According to these improvements the operation of applying the clip to the label is 85 much more simple, easy and convenient than applying it to the article which ultimately carries it, and the clip is thus secured far more strongly and advantageously than it would be in most cases if applied directly to such article. The person applying the label has suitable machinery for stitching the label to the goods but he is not ordinarily equipped for applying such a mechanical element and, where it has been found expedient to make such applications, special machinery was required to be installed. The present type or form of label therefore effects very notable economies and provides more satisfactory results in various ways.

I contemplate as being included in these improvements all such changes, variations and departures from what is thus specifically illustrated and described as fall within the scope of the appended claim.

5 I claim:

As an article of manufacture, a woven fabric label adapted for attachment to an article, the label having identifying data such as
10 the name of the manufacturer, distributor or dealer, or his trade-mark thereon, a clip device having a substantially flat base and an integral tongue-like spring element extending therefrom and overlying the plane of the
15 base, said spring element projecting through the label and extending on the front side thereof, said base being secured on the rear side of the label, the construction providing that the article to be held may be passed between the spring element and the portion of
20 the label overlying the base for ready removability.

LEON FREEMAN.
